SOCKET FOR RELAY

Teizo Fujita and Masao Kikuchi, Osaka, Japan, assignors
to Izumi Denki Company Limited, Osaka, Japan

Filed July 31, 1970, Ser. No. 24,247

Claims priority, application Japan Feb. 2, 1970

Term of patent 14 years

Int. Cl. D13—03

U.S. Cl. D26—1

FIG. 1

FIG. 2

FIG. 3

FIG. 7

FIG. 8

FIG. 9

FIG. 1 is a front elevational view of a socket for relay showing our new design,

FIG. 2 is a top plan view thereof,

FIG. 3 is a right side elevational view thereof,

FIG. 4 is a top, front and right side perspective view thereof,

FIG. 5 is an exploded view of FIG. 4,

FIG. 6 is a bottom perspective view thereof, taken from the rear of FIG. 4,

FIG. 7 is a perspective view of a modified form of FIGS. 1-6 wherein the only difference resides in the reduction of parts;

FIG. 8 is a perspective view of a modified form of FIGS. 1-6 wherein the only difference resides in the duplication of parts;

FIG. 9 is a perspective view of a modified form thereof wherein the only difference resides in the duplication of parts as indicated;

FIG. 10 is a perspective view of another modified form of FIGS. 1-6 which is identical thereto as to all undisclosed portions;

FIG. 11 is a perspective view of yet another modified form of FIGS. 1-6 which is identical thereto as to all undisclosed portions except for a reduction of parts as indicated; and,

FIG. 12 is a perspective view of a modified form thereof wherein the only difference resides in the duplication of parts.

We claim:

The ornamental design for a socket for relay, as shown.
